[57] CLAIM

The ornamental design for a combination lamp and open top storage table, as shown and described.

DESCRIPTION

FIG. 1 is a bottom plan view of a combination lamp and open top storage table, illustrating my new design;

FIG. 2 is a side elevational view taken along lines 2—2 of FIG. 1;

FIG. 3 is a perspective view thereof;

FIG. 4 is a side elevational view taken along the lines 4—4 of FIG. 1; and

FIG. 5 is a side elevational view taken along the lines 5—5 of FIG. 1.
